UNITED STATES PATENT OFFICE

2,573,839

SINGLE TRIGGER MECHANISM FOR
DOUBLE-BARREL GUNS

William E. Garrison, Denton, Tex.

Application August 20, 1946, Serial No. 691,750

3 Claims. (Cl. 42—42)

1

This invention relates to firearms, and more particularly to improvements in double barreled arms whereby a single trigger is used.

It is an object of the invention to provide a double barreled gun having but one trigger, one control, double pull, and a manually shifted lever for changing from one barrel to the other without interfering with the aim of the gun.

A further object is to provide a single trigger double barreled gun having means to enable both barrels to be fired in rapid succession by pulling twice on the single trigger.

A further object is the provision of a double barreled gun having safety means which make it impossible to fire both barrels of the gun at the same time.

A further object is that the safety is not released until the handle 23 has reached its full destination.

These and other objects are attained by the novel construction and arrangement of parts hereinafter described and illustrated by the accompanying drawings, forming a part hereof, and in which:

Fig. 1 is a side view, partly in section, of a gun embodying the invention.

Fig. 2 is a plan view of the gun.

Fig. 3 is a plan view of a selector arrangement used in the gun, the selector being in a neutral position so that neither barrel can be fired.

Fig. 4 is a plan view of the selector in a position wherein the left barrel has just been fired.

Fig. 5 is a side view of the selector device.

Fig. 6 is a sectional view of a safety device used in the gun.

Fig. 7 is a sectional view taken on the line 7—7 of Fig. 6.

Fig. 8 is a plan view of a transfer block used in the selector.

Fig. 9 is a side view of a plunger used in the selector.

Fig. 10 is a front elevational view of the transfer block and the parts carried thereby as shown in Fig. 8.

Referring to the drawings, in Figs. 3 and 4, there are shown the usual sears 1 and 2 of a double barreled gun. The sears 1 and 2 are provided, respectively, with pointed lower ends 3 and 4, which have bevelled tips 31 adapted to be engaged by the bevelled tip 30 of a plunger 5, having projecting from its underside a lug 32 arranged to be received in a notch 33 on a block 34 attached to the trigger 8 of the gun. The trigger 8 has attached thereto a pin 36 which serves as a pivot for transfer block 6, which has a groove

2

in which is positioned a coiled spring 7 constantly bearing against plunger 5. The transfer block 6 has two spaced feet 9 and 10 which engage a cam 11 on a block 12 having a lug 13 which is arranged to enter the slot 42 of post 14 or to engage the inclined sides 40 of the post.

The block 12 is fixed to a shaft 16, which has a pin 37 projecting into a hole 38 in the trigger 8. The shaft 16 moves in a tube 17 which has a slot 18 in which moves a pin 19, the latter passing through the shaft 16. A spring 20 bears against the upper end of shaft 16 and against a stub shaft 22, having a handle 23 connected thereto. A pin 21 passes through the stub shaft 22 and the tube 17. A detent 45, see Fig. 1, holds the safety handle 23 in a definite centered position. When in this position, the lug 13 is in slot 42, and neither barrel of the gun can be fired, as the pull of the trigger is limited by the lug 13 in slot 42.

To fire either barrel of the gun, the handle 23 is moved to the left or to the right, moving lug 13 out of slot 42 and up against the inclined sides 40 of post 14. (See Fig. 5.) Viewing Fig. 6 it will be seen that the handle 23 is coupled to the tube 17 by the pin 21. The shaft 16 carrying the block 12 on which is formed the lug 13 being coupled to the tube 17 by the pin 19, thus as the handle 23 is moved to the left or to the right the structure previously described will cause the lug 13 to move out of the slot 42. The cam 11 engages one of the feet 9 or 10 of the transfer block 6, which pivots about pin 36, and moves the lug 32 of the plunger 5 beneath one of the ends 3 or 4 of the sears, 1 or 2, the movement of the block 6 being limited by engagement of the feet 50 with the pins 51, to properly align the bevelled tip 30 with the bevelled tips 31 of the sears 1 and 2. The movement of the block 6 is further facilitated by a roller 35 pivoted to plunger 5. (See Fig. 9.) When pressure is exerted on the trigger, it will rise as shown in Fig. 5, raising the lug 32 and the rear end of a selected sear, to slide over the bevelled tip 30 of the plunger 5 allowing the selected barrel to fire.

When the handle 23 is in position to fire the right barrel and the trigger has been squeezed for the firing of the right barrel the rear end of the right sear will be engaged by the lug 32. Thus as the lug 32 is moved upward by the action of the trigger the lug will raise the rear end of the right sear and allow the rear end to ride upwardly over the bevelled tip 30 of the plunger 5 firing the right barrel. Then the trigger is fully released to move forward, and the handle 23 is moved into position to fire the left barrel.

The plunger 5 is provided with oppositely extending wings 5' and 5'' and after the right barrel has been fired and the handle 23 moved to fire the left barrel the left wing 5'' of the plunger 5 will be moved into position under the rear end of the left sear. Thus the wing 5'' guides the plunger 5 in its lateral movement. The reverse of this would occur should the left barrel be fired first. Thus the lug 32 of plunger 5 is underlying the rear end of the left sear ready to 10 fire the left barrel at the next pull of the trigger. Thus the lug 32 of plunger 5 fires either barrel if the lever is transferred from one position to the other before firing or if transferred between the fires will fire the unfired barrel. 15

If left barrel is selected first the operation is carried out in the opposite order.

The respective barrels can be fired only after the handle or selective lever 23 has been moved to either the right or left position unless of course 20 the fired hammer has been recocked. It does not make any difference which barrel is selected first, the other barrel will be placed immediately in position for firing in rapid succession by manual movement of the handle 23.

The successive firing of the barrels is attractive to sportsmen who usually do not care to fire both barrels at one time; and the safety features of the device are positive and make it impossible to fire both barrels simultaneously.

The above description is to be considered as illustrative and not limitative of the invention, of which modifications can be made without departing from the spirit and scope of the invention as set forth in the appended claims.

The invention having been described, what is claimed is:

1. A firing mechanism for a double barrelled gun having a pair of sears to hold firing pins in a cocked condition, comprising a single trigger, 40 a transfer block pivotedly mounted on the trigger, a spring pressed plunger carried by the block, a bevelled tip on the forward end of the plunger.

engaging the rear ends of the sears, wing portions extending from the forward end of the block in opposite directions to each other and disposed below the bevelled tip on said plunger, a pair of forwardly extending feet on said block below the wings on said plunger, a handle, a tube for mounting said handle rearwardly of said transfer block, means on said tube engaging said block for the pivoting thereof, so that the tip on said plunger will selectively engage the undersurface of the sears to fire one barrel of the gun and upon subsequent movement of the handle to fire the remaining barrel and the wings on said plunger guiding the plunger below the sears during the lateral movement of said transfer block.

2. A firing mechanism as in claim 1 wherein the forward end of said plunger is provided with a forwardly extending lug, and a roller is mounted in said lug to facilitate the shifting of the block beneath the sears.

3. A firing mechanism as in claim 1 wherein a second block is fixed to said trigger forwardly of said transfer block, and a lug carried by said plunger forwardly thereof is adapted to engage the second block to retain said transfer block in safety position.

WILLIAM E. GARRISON.
